[57] **CLAIM**

The ornamental design for a tamper proof tray for hypodermic syringes, as shown and described.

DESCRIPTION

FIG. 1 is a top plan view of a tamper proof tray; FIG. 2 is a side view;

FIG. 3 is an end view of one end;

FIG. 4 is an end view of the other end;

FIG. 5 is a sectional view taken generally along lines 5—5 of FIG. 1;

FIG. 6 is a sectional view taken generally along lines 6—6 of FIG. 1;

FIG. 7 is a sectional view taken generally along lines 7—7 of FIG. 1;

FIG. 8 is a bottom view;

FIG. 9 is a perspective sectional taken generally along lines 9—9 of FIG. 1;

FIG. 10 is a top plan view of an alternate embodiment of a tamper proof tray;

FIG. 11 is a side view thereof;

FIG. 12 is an end view of one end thereof;

FIG. 13 is an end view of the other end thereof;

FIG. 14 is a sectional view taken generally along lines 14—14 of FIG. 10;

FIG. 15 is a sectional view taken generally along lines 15—15 of FIG. 10;

FIG. 16 is a sectional view taken generally along lines 16—16 of FIG. 10; and

FIG. 17 is a bottom view of the embodiment of FIG. 10.
